UNITED STATES PATENT OFFICE

MEYER D. POLAND, OF WILMINGTON, DELAWARE

DESIGN FOR A FINGER RING

Application filed December 16, 1931. Serial No. 42,098. Term of patent 7 years.

To all whom it may concern:

Be it known that I, MEYER D. POLAND, a citizen of the United States, residing at Wilmington, in the county of New Castle and State of Delaware, have invented a new, original, and ornamental Design for Finger Ring, of which the following is a specification, reference being had to the accompanying drawings, forming a part thereof.

I claim:

The ornamental design for a finger ring, as shown.

MEYER D. POLAND.
